ROLLING WINDOW SCREEN

Julius Herr, New York, N. Y.

Application September 18, 1933, Serial No. 689,807

9 Claims. (Cl. 156—39)

This invention relates to devices such as rolling window screens.

One object of the invention is to provide a device of the character described having improved means for mounting a window screen roller so as to facilitate repair or replacement with particular reference to the screen, and to permit removal of the screen and roller from the window casement in a highly simplified manner, if such removal be necessary.

Another object of the invention is the provision of a device of the nature set forth having improved means associated with a screen movable into a window casement or frame, so as to render the latter weatherproof as against entry of rain thereinto.

A further object of the invention is to furnish a device of the nature set forth having relatively few and simple parts, and which is inexpensive to manufacture, adapted to be embodied with widely different types of windows, which is conveniently operated by a person with little or no mechanical skill, which is neat in appearance, compact in arrangement, durable, reliable and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in front elevation of a device embodying the invention, with the sashes partly open.

Fig. 2 is an enlarged fragmentary sectional view taken on line 2—2 of Fig. 1.

Fig. 3 is a fragmentary sectional view taken on line 3—3 of Fig. 2.

Fig. 4 is an enlarged sectional view of the weather proofing element, showing a slightly modified arrangement.

In devices of this character heretofore known, it has been difficult to remove the screen and roller when desired, and has required considerable mechanical skill to accomplish such removal. By my invention this can be done in a particularly simplified manner by anyone.

The advantages of the invention as here outlined are best realized when all of its features and

instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a device embodying the invention. The same may include a window frame 11 which may be a standard stock or special window frame of varying size, construction and arrangement. Said frame may include the head and sill portions 12, 13, 15 respectively, and the side uprights 14. The window frame may be provided with suitable means for guiding sashes, such as, for example, the respective upper and lower sashes 15 and 16, and the guide means may be in the nature of the channels 17 and 18 for the respective sashes, these channels being separated by the parting strip 19. The sash 15 may include the usual head rail 20, and the sash 16 may have a sill rail 21, the screens being connected to these rails as hereinafter described. It will be understood that the illustration of a window as herein shown is conventional, but that the invention is not limited thereto, and other window constructions may also be used.

In general, it may be noted that the window frame structure may bear any suitable relation to the thickness of the wall, and may be arranged in any manner well known in the art. The window frame is modified by this invention in that it includes upper and lower pockets, chambers or movable compartments, in the head and sill 12, 13, and openings or slots being provided in the head and sill in communication with said compartments for movement of screens from said compartments along the window frame, as by connection with the individual upper and lower sashes, whereby a screen and its respective sash is movable as a unit. Since the structure for the head of the frame is merely the inverted form of that used at the sill of the frame, only the latter is shown and described in detail herein.

The sill portion of the window frame may include a longitudinal pocket or chamber 22 extending therealong, for example, in a horizontal direction. If desired, this chamber may be formed wholly in the wall 23 into which the window frame is set, or partly in said wall and partly in the frame, or wholly in the frame. As the term window frame is used herein, it may

comprehend any necessary portion of the wall 23, according to the construction used, and the term window is to be understood as including any desired closure or ventilation control.

5 The chamber 22 may be closed on top by the sill element 24 which may have an opening or slot 25 extending longitudinally thereof and arranged to communicate with the chamber and to align with the proper cooperating sash, in this 10 case, the lower sash 16.

Movably or slidably mounted in the chamber 22 is a supporting means 26. The latter may, for instance, be in the nature of a drawer which may have one or more walls, such as a bottom wall 15 27 and a front wall 28. The drawer is thus of substantially skeletonized construction so as to be light in weight and inexpensive in construction. This drawer is movable inwardly, that is, toward the left, through an opening 29 that may 20 be formed in the front face element 30 of the window frame. If desired, the drawer may be wholly removable from said chamber, but in the closed position shown, the wall 28 of the drawer may lie substantially in the plane of the frame 25 element 30 so as to afford a finished appearance. The drawer may be locked shut in any suitable manner as by easily removable screws 31, and may be fitted in the frame along angular lines 29a.

30 Mounted in the drawer 26 is a feeding means 32 for flexible or pliable element, that may consist of a suitable fabric, or sheet material, as, for example, a screw 33. Said feeding means 35 may be in the nature of a conventional window shade roller 34 having the usual internal coil spring (not shown) for tending to cause the roller to wind up the screen thereon. The roller differs merely in that the usual ratchet and dogs for stopping the roller in a desired position are 40 omitted. Said roller may be removably mounted in a well known manner, as by axial-end pins 35 journaled in brackets such as 36 secured to the drawer bottom 27 as at 37. At least one of the 45 brackets may have an angular slotted bearing 38 for removably receiving its coacting pin 35.

It will be understood that the screen feeding or control means 32 is disposed in suitable operative juxtaposition to the slot 25. If the depth of 50 the window frame is greater than shown, the drawer bottom 27 may be correspondingly increased in size, as will be obvious.

The screen 33 may extend the full width of the sash and the slot 25 may be correspondingly long. Free edges of the screen may be reenforced 55 in a suitable manner by closer weaving, or by suitable tapes or strips such as 39 and 40, the former of which may be secured along the side edges of the screen, and the latter along the free end thereof. These strips may consist of fabric, 60 metal, or composition material.

The screen 33 is preferably detachably connected to the sash, at an adjacent rail thereof as by providing the sill rail 21 of the sash 16 with a rabbet, groove or undercut 41 in which the connection is made. Various types of connecting means may be used, and for illustrative purposes, I show a plurality of headed pins or screws 42 secured to the sash, the screen having keyhole slot openings 43 in the reenforcement 40, for 65 detachably receiving and engaging over said screws. As thus arranged there is no projection on the sash.

To prevent the entrance of rain through the slot 25, a suitable weatherstripping or deflector 70 75 44 is provided adapted to slidably engage the

screen on the outer face thereof, in such manner as not to interfere with the up and down movement thereof. Preferably also, the deflector is movable, so that should the screen be disconnected from the sash and removed from the slot passage 25, the deflector will be movable downward to cover and close the slot. Said deflector may be omitted at the head of the window frame.

5 The deflector 44 may include a plate 45 having a thin sheet of pliable fabric or rubber 46 extended thereover and having along its longitudinal edges oppositely formed beads 47, 48 within which the sheet is clamped. The lower bead 48 may have a rod 49 extending therethrough and suitably journaled in the uprights 14 of the window frame. The upper bead section 47 may have a relatively large radius for wiping contact with the screen. Said deflector 44 may be mounted in a recess 50 of the frame element 24 as shown in Fig. 2, or on the upper surface of the sill as shown 10 in Fig. 4. In the latter case, the sash may merely come to rest on the deflector, in the closed position. A weak leaf or wire spring 51 may be slidably engaged over the lower bead structure as at 15 52 and may rest on the bottom of the rabbet with 20 an end 53 of the spring bearing upward on the deflector to tend to elevate the same. The springs 25 may be provided at opposite ends of the deflector. 30

In operation, when a sash is raised or lowered the screen connected thereto is correspondingly moved and winds or unwinds automatically on its roller. Thus the screen is exposed only to the extent that the window is open. In case it rains, the water running down the screen is deflected by the means 44 so as not to enter the window 35 frame. If the lower sash is closed, the means 44 is depressed into the recess 50, so that the upper-bead section moves the screen laterally and substantially closes the slot opening 25. When the sash is again raised, the means 44 is frictionally 40 elevated, with the aid of spring 51. The weight of the means 44 may normally be relied upon to hold the same in suitable contact with the screen. The entire arrangement is such that binding or 45 jamming with the screen is avoided. If a person desires, he may readily detach the screen from the window, at the inner face thereof. If the screen and roller are to be removed for replacement or repair, it is merely necessary to remove the drawer screws, and withdraw the screws, after 50 which the roller may be disengaged from its brackets in the usual manner. It will be noted that the tension of the roller spring will affect the counterbalanced condition of the sash, and hence any suitable sash locks such as 54 may be provided 55 to hold the sash in predetermined position.

It will be appreciated that various changes and modifications may be made in the device as shown in the drawing, and that the same is submitted in an illustrative and not in a limiting sense, the 60 scope of the invention being defined in the following claims.

I claim:

1. In a window having a window frame, a compartment associated with and extending horizontally along said frame and having an opening at the front face of the frame, an angle member extending longitudinally of said compartment and having a bottom wall and a front wall, said bottom wall slidably resting on the bottom of said compartment, said front wall closing the opening of said compartment, the front and bottom walls of said angle member being interconnected for bodily horizontal movement as a unit slidably into and out of said compartment, a roller having 65 70 75 80 85 90 95 100

- 5 a flexible element, said roller being operatively mounted on said member, said compartment having a slot opening extending therealong through which said element is movable in operative relation along the window frame, and said compartment being otherwise closed.
6. In a device having a window frame, a compartment adapted to adjoin the latter and having an opening at a face of the frame, a carrier in the 10 compartment, a roller having a flexible element, said compartment having a slot for the element, said roller being operatively mounted on the carrier to maintain the element in operative relation for movement through said slot and along 15 the window frame, said carrier having a front wall for closing the face opening of said compartment said carrier having a bottom wall permanently connected to a bottom portion of the front wall and slidably resting on the bottom of 20 said compartment, said front wall having a top free edge portion having rabbeted connection with an adjacent wall portion of the compartment, and means releasably connecting said top free edge portion of the front wall with the compartment 25 wall at the rabbeted connection, said carrier being otherwise free of and independent of said compartment, and the latter being otherwise closed, as set forth.
7. In a window frame, a wall member having 30 a slot, a flexible screen movable therethrough, means for supporting a section of the screen in extended condition through the slot, and means extending along the slot in close overlying proximity thereto and in yieldable contact with the 35 screen section continuously therealong, said means being inclined downwardly and away from the screen section so as to deflect water against passing through the screen section.
8. In a window frame, a wall member having 40 a slot, a flexible screen movable therethrough, means for supporting the screen in partially extended condition, said member having a recess extending along the slot in communication therewith, and means in said recess pivotally mounted 45 therein and having contact with the screen along a continuous line, said means being inclined downwardly away from the screen toward the pivotal axis, as set forth.
9. In a window frame, a wall member having 50 a slot, a flexible taut screen movable therethrough, said member having a recess extending along the slot in communication therewith, and a deflector extending continuously along said recess and pivotally mounted therein for yielding engagement with the screen, said deflector being swingable wholly into the recess and partially out of the recess about the pivotal axis.
10. In a window frame, a wall member having a slot, a flexible screen tautly movable therethrough, said member having a recess extending along the slot in communication therewith, and a deflector extending continuously along said recess and pivotally mounted therein for yielding engagement with the screen, said deflector being swingable wholly into the recess and partially out of the recess about the pivotal axis, and resilient 15 means tending to swing the deflector partially out of said recess.
11. In a window frame, a wall member having a slot, a flexible screen movable therethrough, means for movably supporting the screen, said member having a recess extending along the slot in communication therewith, and a deflector extending continuously along said recess and pivotally mounted therein for yielding engagement with the screen, said deflector being swingable wholly 20 into the recess and partially out of the recess about the pivotal axis, and resilient means tending to swing the deflector partially out of said recess, said resilient means being secured about the pivotal axis of the deflector and having abutment 25 in the recess with a portion of said wall.
12. In a window frame, a wall member having a slot, a flexible screen movable therethrough, means for maintaining the screen in position for said movement, an elongated deflector extending 30 along the screen and having a pivotal axis parallel to the screen and spaced therefrom, said deflector being inclined from said pivotal axis upward into 35 contact with the screen.
13. In a window frame, a wall member, having a slot, a flexible screen movable therethrough, means for holding the screen with a portion thereof adapted to lie in the plane of said slot, an elongated deflector extending along the screen portion 40 and having a pivotal axis parallel to the screen portion and spaced therefrom, said deflector being inclined from said pivotal axis upward into 45 contact with the screen portion, and resilient means tending to maintain the deflector in the inclined position.

JULIUS HERR.
